UNITED STATES PATENT OFFICE.

ALFRED C. EINSTEIN, OF ST. LOUIS, MISSOURI.

ACETYLENE-GAS GENERATOR.

SPECIFICATION forming part of Letters Patent No. 693,248, dated February 11, 1902.

Application filed January 2, 1901. Serial No. 41,840. (No model.)

To all whom it may concern:

Be it known that I, ALFRED C. EINSTEIN, a citizen of the United States, residing in the city of St. Louis, in the State of Missouri, have 5 invented certain new and useful Improvements in Acetylene-Gas Generators, of which the following is a full, clear, and exact description, reference being had to the accompanying drawings, forming part of this specification.

My invention relates to a generator for the production of acetylene gas, and has particular reference to a feed - valve construction whereby the carbid is automatically deposited in the water, by which it is decomposed, according to the requirements of the generator.

My invention consists in features of novelty hereinafter fully described, and pointed out in the claim.

Figure I is a vertical sectional view taken through my improved generator and the gasometer associated therewith. Fig. II is an enlarged detail view of a modification of the carbid-delivering valve. Fig. III is a longitudinal sectional view of another modification of the valve. Fig. IV is an enlarged cross - sectional view taken on line IV IV, Fig. I.

1 designates the tank of the generator, suitably supported and containing a water and gas chamber 2.

3 designates a carbid-receptacle mounted in the upper end of the tank 1 and closed by a cap 4 of the tank. The receptacle 3 is preferably of hopper shape, as shown, in order that the carbid placed therein may fall by gravity to a central position at the bottom of the receptacle. Access to the interior of the receptacle 3 is provided for by a hand-hole 5, closed by a cover 6. The cap 4 is provided with a stuffing-box 7, containing suitable packing retained by a gland 8. Depending from the carbid-receptacle 3 is a stuffing-box 9, containing a compressible packing 10, that is confined by the cap 11.

12 designates the feed-valve, that operates through the stuffing-boxes 7 and 9 and through the carbid-receptacle 3. The valve 12 is of such length that it may be projected downwardly into the chamber 2 within the tank 1 and also extends exterior of the upper end of

the tank for manipulation, as will hereinafter appear. Extending through the feed-valve 12 are a series of ducts 13, that lead in downward diagonal directions therein, said ducts being designed to communicate with the interior of the carbid-receptacle 3 and also designed to communicate with the chamber 2, to deliver carbid thereinto from the receptacle on the movement of the feed-valve.

The feed-valve may be of different forms of construction. In Fig. I, I have shown it comprising a solid rod having the ducts extending obliquely therethrough and in lines parallel with each other.

In Fig. II, I have shown the feed-valve (designated by 12^a) with ducts 13^a, extending diagonally therethrough, but positioned in spiral arrangement.

In Fig. III, I have shown the feed-valve 12^b of tubular form with small tubes extending diagonally therethrough to form the ducts 13^b, this latter construction affording a minimum of weight.

In the practical use of the apparatus the feed-valve is operated to deliver the carbid from the receptacle 3 into the chamber 2 by a suitable construction, such as will now be described.

14 designates a gasometer-tank into which the gas-pipe 15 leads from the chamber 2 of the generator-tank, and 16 is the gasometer-bell. The bell 16 carries an arm 17, equipped with a foot 18, that is adapted to bear against the upper end of the feed-valve 12.

19 is a counterbalance-weight carried by a rocking lever 20, that is pivoted to a standard 21 and bears against a roller 22, mounted in the feed-valve.

During the operation of the apparatus in the generation of gas the combined weight of the valve 12, the bell 16, and parts carried thereby causes the valve to be moved downwardly whenever the gas in the gasometer is insufficient to hold the bell 16 elevated. In such downward movement of the valve a charge of carbid equal to the holding capacity of the ducts 13 is carried in said valve downwardly therewith and discharged into the chamber 2, where it falls into the water therein to be decomposed and cause the generation of acetylene gas. As each duct 13 of the series in the valve 12 passes through the

carbid-receptacle it receives a charge of carbid. If the amount of carbid delivered from the first duct 13, that discharges into the water in the chamber 2, is insufficient to cause the generation of the requisite amount of gas, the valve continues to descend, owing to lack of support by gas previously generated and conveyed to the gasometer, and additional carbid is delivered from the upper ducts 13 until the requisite amount of gas has been generated, according to the capacity of the apparatus. As soon as the gas-pressure is sufficient in the gasometer to raise the bell 16 the valve 12 is elevated by the counterbalance-weight 19 and is upheld in position to receive a fresh supply of carbid until such time as the supply of gas becomes diminished, when the feeding operation of the carbid is again resumed in the same manner as before. 20 23 designates a drain-pipe applied to the

lower end of the tank 1 and provided with a valve 24, through which the chamber 2 may be flushed.

I claim as my invention—

In an acetylene-gas generator, the combination of a tank provided with a water-chamber, a carbid-receptacle, a vertically-slidable valve or carrier arranged to slide through said carbid-receptacle, and provided with a series of apertures extending diagonally and downwardly therethrough, and means for moving said valve up and down to convey the carbid deposited in said apertures from said receptacle to said water-chamber, substantially as described. 25 30

ALFRED C. EINSTEIN.

In presence of—

E. S. KNIGHT,
N. V. ALEXANDER.
